UNITED STATES PATENT OFFICE.

PETER SPILMAN, OF RICHMOND, VIRGINIA.

APPARATUS FOR LAYING OFF THE SCYE IN CUTTING GARMENTS.

Specification of Letters Patent No. 11,339, dated July 18, 1854.

To all whom it may concern:

Be it known that I, PETER SPILMAN, of the city of Richmond, county of Henrico, and State of Virginia, have invented a new and 5 Improved Apparatus for Locating the Armholes of Coats; and I do hereby declare that the following is a full and exact description thereof, reference being had to the accompanying drawings and to the letters of reference marked thereon.

The nature of my invention consists in an apparatus by means of which, after obtaining certain measures, I can with precision locate the armhole to be cut out of a piece of 15 cloth intended for a coat.

Figures 1 and 2 represent sufficient of a man's figure, to show how the square rule is applied, and also to show the points from which measurements are taken. Fig. 3 is a 20 diagram showing the manner of constructing my apparatus for laying off armholes; Fig. 5, shows the apparatus for laying off armholes; Fig. 6 shows the back piece of the coat, cut from the cloth in the usual 25 manner; Fig. 7 shows the mode of using my apparatus Fig. 5 on the cloth.

There being so many different figures, and referring to different things, the letters on these figures do not and could not indicate 30 corresponding parts.

My apparatus is constructed as follows, see Figs. 3 and 4: Take a stiff paper board; on this, draw two lines A, and B, forming a right angle; from their point of intersection 35 a, lay off on the line A, one and one-eighth ($1\frac{1}{8}$) inches to the point b; from the point a, lay off six inches on the line B, to the point c; join b, c; from the point b, lay off $1\frac{1}{8}$ inches on the line b, c, to the point d. 40 At the point c, draw the line C, at right angles to the line B; and on this line C, from the point c, lay off $1\frac{1}{4}$ inches to the point e; join b, c; on the line b, c, from the point b, lay off $4\frac{3}{8}$ inches to the point f; join d, f; 45 divide the line d, f, into 24 equal, or nearly equal parts.

The mode of numbering the divisions of the line d, f, and of the other numbered lines, will be explained further on. From 50 the point e, on the line C, lay off $1\frac{1}{4}$ inches to the point g; join b, g; from b, on the line b, g, lay off $3\frac{1}{4}$ inches to the point h; divide g, h; divisions and numbers on this line the same as on the line d, f. From g, on line C, 55 lay off $3\frac{1}{4}$ inches to i; join b, i; from b, lay off $3\frac{3}{4}$ inches to j; divide and number i, j,

in the same manner with d, f. From i, on line C, lay off $8\frac{5}{8}$ inches to k; join b, k; from b, on line b, k, lay off $3\frac{3}{4}$ inches to l, and $7\frac{1}{2}$ inches to m; divide and number l, m, 60 in the same manner with d, f. At k, draw line D, at right angles to line C; on D, from k, lay off 8 inches to n; join b, n; from b, on b, n, lay off $3\frac{3}{8}$ inches to o, and $7\frac{3}{8}$ inches to p; divide and number o, p, in the same 65 manner with d, f.

The numbers seen in the diagram, Fig. 5, are determined in the following manner: They are the measurements, which in practice, are taken by the common inch line used 70 by tailors, from the point a (Fig. 1), over the shoulder and following the seam of the armhole, to the point b (in Fig. 2); the positions of these two points will be described hereafter: the number $9\frac{3}{8}$, which is the lowest 75 number seen in the diagram, is the shortest measurement which would probably be taken in inches between the two points a (Fig. 1) and b (Fig. 2); it would be the measure of a small sized boy: the number $16\frac{3}{8}$ is the corresponding measure of the largest sized man: the difference between these two numbers (9 $\frac{3}{8}$ and 16 $\frac{3}{8}$) is divided into 24 parts, as nearly equal as will be necessary, or convenient in using the inch tape line; and 80 these results give the numbers to be applied to the 24 sub-divisions, already described, into which Nos. 1, 2, 3, 4, 5, Figs. 1 and 2, have been divided.

The square rule which I use differs somewhat from that in ordinary use; Fig. 4^a is a side view, and Fig. 5^a, a plan of my rule; its form is shown very plainly in Figs. 1, and 2. I do not claim this rule in this 90 application.

The operation of my apparatus is as follows; I place the rule across the back of the person as shown in Figs. 1 and 2, its general direction being horizontal; the long arm c, is placed across the back, and the short 95 arm d, snug up under the arm: mark with a chalk, the intersection e, of the upper edge of the rule and the back seam of the coat; mark the coat at the point a, directly opposite to the angle of the rule; mark also a point b, (Fig. 2) where a vertical line tangent to the seam of the sleeve intersects the upper edge of the rule: the rule is now dispensed with.

For purposes of explanation, I will assume a certain measurement of a man: suppose 110 the measure, by an inch line, from e, around the body to b, to be 12 inches; I have found

that the point *a* (Fig. 1) is generally midway between *e*, and *b*; *e a*, and *a b*, are therefore in this assumed case, equal to six inches each: from the top *g* (Fig. 1) of the back 5 seam, measure across the shoulder and down to the point *b*; suppose this to be 13 inches; from the point *a* (Fig. 1) across the shoulder and along the armhole seam, to *b*, (Fig. 2) suppose $12\frac{5}{8}$ inches: these three are the only 10 measures required for my apparatus; the other measures, as for the back, collar, front, &c., are taken in the usual manner; the back is cut from the cloth in the ordinary way, allowing about $\frac{1}{4}$ of an inch in width, over 15 the measure, for a proper looseness of fit (see Fig. 7.) Now, to use my apparatus, and lay off the armhole on the cloth to fit the assumed person: suppose Fig. 8 to be the piece of cloth: draw a line *A*, with 20 chalk, about an inch from its back edge, and parallel with this edge; at a distance of five inches from this line, draw a line *B*, parallel with it; this five inches, together with the extra size given to the back, as mentioned 25 above, will be the assumed measurement from *e* to *a*: draw a line *C*, on the cloth, at right angles to *A*, and *B*: the position of this line *C*, is not material, but should be placed so that the cloth will not waste in 30 cutting: the assumed measure from *a*, across the shoulder to *b*, being $12\frac{5}{8}$ inches, find the points marked $12\frac{5}{8}$ on the Nos. 1, 2 and 3, of the diagram, Fig. 5: (It should have been stated that a longitudinal slit is cut along 35 each of the Nos. 1, 2, 3, &c., in my apparatus, so that the cloth may be marked with a pointed chalk opposite to each one of the divisions on these numbers.) The point $12\frac{5}{8}$ on No. 1 (Fig. 5) must be placed on the line 40 *C*, and those on Nos. 2, and 3, must be placed on the line *B*; mark on the cloth, opposite to all the Nos. 1, 2, 3, 4, and 5, of diagram, Fig. 5: draw a curve through these points, in the usual method of tailors, and you will have 45 the part of the armhole from *a* to *b*, Fig. 8; continue this curve from *b*, to the point *c*, on line *A*, one inch from intersection of lines *A*, and *C*, and you will have the entire curve of the armhole for the measure as- 50 sumed.

To get the "shoulder" of the coat; draw a line *D*, on the cloth, parallel to *C* (Fig. 8) and 13 inches from it, (13 inches being the assumed measure) from *g* (Fig. 1) over and 55 down the shoulder to *C* (Fig. 2): now, hav-

ing the back cut out of the cloth, (Fig. 7) the curve of the armhole laid off on it, and the line *D* determined by the measure from *g* to *b*, the manner of cutting out the shoulder of the coat is familiar to all tailors. 60

It will be readily seen that my invention does not consist in any system of measurement, although a few measures must be taken, and taken in a particular manner, before my apparatus can be applied. I do not 65 profess to be able to locate the position of the armhole in the coat; but when its position is determined by the ordinary measures, my apparatus gives the precise curve to the armhole: armholes determined by this apparatus 70 will be found nearly circular, and will cause the sleeve to fit easily in coats of all shapes. It is not easy to give a demonstration of the problem presented by this apparatus; I believe that its operation is now as perfect as 75 practicable; and this has been attained only after continuous attempts carried on through several years.

It must be understood that my apparatus does not lay off the armholes of a uniform 80 curve, varying only in size, to suit different sized persons; but the form of the curve changes with the size and with the shape of the person; so that whether the back be broad or narrow, the chest deep or thin, the 85 shoulders erect or stooping, the curve laid off on the cloth will invariably be found to give an armhole of a smooth and graceful fit. And in this important point—that of accom- 90 modating itself to every shaped person—my invention will be found to differ from all those heretofore attempted.

I do not claim the laying down of lines on 95 a diagram, for determining points of the armholes of the coats, considered irrespec- 100 tive of the precise manner in which these lines are placed relatively; for I know that diagrams, with lines on them, but differing entirely from those which I have invented, have heretofore been made; but

What I claim as my invention, is—

The apparatus consisting of the diagram, Fig. 5 in the drawings, constructed and operating in the manner and for the purposes described in the specification and drawings. 105
